UNITED STATES PATENT OFFICE.

GEORGE H. ISLEY, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

METHOD OF AND APPARATUS FOR REVERSING AND CONTROLLING REGENERATIVE FURNACES.

Application filed April 13, 1922. Serial No. 552,304.

To all whom it may concern:

Be it known that I, GEORGE H. ISLEY, a citizen of the United States, residing at Worcester, in the county of Worcester and 5 Commonwealth of Massachusetts, have invented a new and useful Improvement in a Method of and Apparatus for Reversing and Controlling Regenerative Furnaces, of which the following, together with the accompanying drawings, is a specification.

The present invention relates to the reversal and control of furnaces of the regenerative type, and provides for changing, at intervals, the direction of travel of the hot 15 gases through the furnace, in order (1) to prevent overheating of the furnace passages and flues, and (2) to raise the temperature, prior to combustion of the entering gases,—either air, or fuel, or both.

20 The invention contemplates radical departures from previous and present practices, in respect of the extreme simplicity of the reversing instrumentalities, and the absence therefrom of the usual dampers and 25 valves, in addition to which is made possible the operation of the furnace, at the highest degree of efficiency, without the need either for the usual stack or the usual complicated system of flues. Other and further advantages of the invention will be made apparent 30 as the following description proceeds, reference being had to the accompanying drawings, wherein—

Fig. 1 is a diagrammatic plan view of the 35 invention as applied to a conventional type of regenerative furnace.

Fig. 2 is a sectional view of the apparatus, illustrating the principles of the invention, and

40 Fig. 3 is an enlarged detail view, partly in section, of one form of apparatus that may be employed for procuring the furnace draft.

Like reference characters refer to like parts 45 in the different figures.

As shown in Fig. 1, the invention is applicable, in general, to any type of regenerative furnace, irrespective of the fuel used therein. In connection with the use of oil, coke oven 50 gas, tar, powdered coal, and the like, as fuel, involving the employment of suitable burners therefor, at each end of the furnace, as shown in broken lines 1, 1', the inven-

tion is applicable to the regenerative heating of the air, for supporting combustion 55 of such fuel, said air being admitted alternately to the furnace by way of suitable regenerator passages 2 and 2'. In connection with the use of producer gas as fuel, the invention is applicable to the regenerative 60 heating not only of the air, but also of said gas, the latter being admitted alternately to the furnace by way of suitable regenerator passages 3 and 3'.

In its simplest form, the invention contemplates the connection of the air regenerator passages 2, 2' to open-ended ducts 4, 4' respectively, each preferably in the form of a Venturi tube and equipped at or near its throat portion with a suitable drafting or 65 blowing device, such as the fan 5, Fig. 3. The two fans 5, 5' are driven by reversible motors 6, 6' respectively, and in connection with the passage of gases through the furnace from left to right, as shown in Fig. 1, 70 (the right hand burner 1' being retracted and inoperative), the motor 6 is caused to drive the fan 5 in such a direction as to draw in air through the upper open end of duct 4, forcing it through passage 2 into the left 75 hand end of the furnace, while the motor 6 is caused to drive the fan 5' in the opposite direction, so as to draw the burned waste gas from the right hand end of the furnace into the duct 4', expelling same from the 80 upper open end of said duct. Assuming the use of a form of fuel whose admission 85 to the furnace is by the use, alternately, of the burners 1, 1', the above described apparatus is all that is requisite for the reversal, 90 when desired, of the furnace, it being understood that the exit of combustion products is by the way of the passage 2 or the passage 2', as the case may be,—the passages 3, 3' and also the passages 7 and 7', 95 hereinafter referred to, being either blanked off or non-existent.

The reversal of the furnace, under the conditions assumed, is effected by simply changing the direction of gaseous flow 100 through the ducts 4, 4', i. e., by reversing the motors 6 and 6', and by causing the fuel supply to be furnished by burner 1', instead of burner 1. This causes the cool entering air to be regeneratively heated in the passage 2', while the products of combustion 105

pass out through the passage 2, and impart their heat to same, preparatory to the subsequent introduction of air through said passage at the next reversal of the furnace. 5 It is to be noted that the apparatus affords positive control over both ingoing and outgoing gases, owing to the fact that the mechanical drafting devices are susceptible of any manipulation or variation that may 10 be desired. In other words, the separate and independent control and operation of the two reversible motors 6 and 6' gives to the apparatus, wholly apart from the use of any dampers or valves, the widest possible 15 latitude and flexibility in meeting all the various conditions of furnace operation. For instance, under normal conditions of operation, the blower on the outgoing side of the furnace must be able to handle a 20 greater volume of gases than the blower on the ingoing side, due to the increase of volume under high temperature; this is made possible by the independent control of the motors, which permits one to be operated 25 at a higher speed than the other. Again, the atmospheric conditions may at times be such as to require very little mechanical assistance in drafting the furnace; at such times, either one or both of the blowers may 30 be slowed down, or may be rendered wholly inoperative.

Or, if desired, by slowing down the motor 6 or 6' on the outgoing side of the furnace, the rate of discharge of burned gases may 35 be so retarded as to cause said gases to leave substantially all of their heat in the walls of the regenerator passage 2 or 2'; and in the same way, on the ingoing side, the entering air may be caused to absorb, in varying 40 quantities and at various rates, the heat of the passage walls. If it be desired to cool the regenerator passages for repairs or otherwise, this can be done in one-half the time ordinarily required, simply by operating 45 both blowers 5 and 5' to force in air through each duct 4 and 4', thus holding the heat in the furnace while repairs are being made. To cool the furnace proper for purposes of repair, both blowers 5 and 5' are 50 operated in the discharging direction, to draw out all gaseous products through the passages 2 and 2'; the present invention permits of this cooling in half the time required when the usual types of reversing apparatus 55 are employed.

The same advantages are obtainable when producer gas or the like is used as a fuel in the furnace, being admitted alternately at either end, by the passages 3, 3'. The construction, in such event, involves the disposal of the terminal of passage 3 adjacent the terminal of a gas supply flue 8, and the terminal of passage 3' adjacent the terminal of a gas supply flue 8', the two supply flues 65 8, 8' being connected to any suitable source

or sources of producer gas supply, not shown. At the left hand side of the furnace, a flue or connection 7, branching from the passage 2, has its terminal adjacent to the terminal of passage 3, and on the opposite side thereof from the terminal of flue 8; this construction is duplicated at the right hand side of the furnace in a flue or connection 7', forming a branch of the passage 2'. Each set of flue terminals 3, 7, 8, and 3', 7' and 8', has associated therewith a reversing device, consisting in part of a shiftable hood 9, adapted in one position to span and connect the terminals of flues 3 and 8 (or 3' and 8'), and in the other position, to span and connect the terminals of flues 3 and 7 (or 3' and 7'). The terminals of flues 7, 8, 7', 8' are equipped with pivoted gravity closing covers 10, 10, of the general form and mode of operation described and claimed in my United States Letters Patent No. 1,408,946; these covers 10, which are adapted to cooperate with the water in pans 11 to seal their respective terminals, are provided with projecting ears or lugs 12, for engagement by the edge or skirt of the associated hood 9, whereby movement into open position is automatically effected when said hood is moved to cover, inclose and seal the cover-equipped flue. Reversing apparatus of this construction, except as combined with the novel arrangement of parts herein claimed, forms no part of the present invention, being fully described and claimed in the aforesaid Letters Patent; it is to be understood that any other suitable type of apparatus for reversing the gas supply may be used.

In the position of the parts shown in Figs. 1 and 2, with the left hand hood 9 at its extreme left hand position, the entrance of gas to the furnace is by way of passages 8 and 3, the hood 9 holding the closure of flue terminal 8 in open position, as shown, and the connection 7 being blanked off by its cover 10. The introduction of air to the left hand side of the furnace takes place in the manner previously described. At the right hand side of the furnace, the hood 9, in its extreme right hand position connects the flues 3' and 7', the gas supply terminal 8' being blanked off by its cover 10, and the products of combustion discharging through the passages 2' and 3' being drawn into the duct 4', as shown. For effecting the reversal of the furnace, the motors 6 and 6' are reversed, and also the hoods 9, 9 are shifted over to the right, thereby causing air and gas to enter at the right hand side, and products of combustion to leave at the left hand side, the latter being drawn out through the duct 4. In this position of the parts, the right hand flue terminal 7' is blanked off, as is also the left hand gas supply terminal 8, by the associated gravity closing covers 10, 10.

I claim,

1. Reversing mechanism for a regenerative furnace, comprising blowing devices associated respectively with regenerator passages at opposite ends of said furnace, and means for independently reversing and for independently controlling the speed of each of said blowing devices.
2. In a regenerative furnace, a blowing device associated with each regenerator passage, and means selectively operable on said devices for causing them either to exhaust gases from both ends of the furnace simultaneously, or to supply air to both of said ends simultaneously.
3. In a regenerative furnace, a blowing device associated with each regenerator passage, and means selectively operable on said devices for causing them either to exhaust gases from both ends of the furnace simultaneously, or to supply air to one end while exhausting gases from the other end.
4. In a regenerative furnace, a blowing device associated with each regenerator passage, and means selectively operable on said devices for causing them to supply air to both ends of the furnace simultaneously, or to supply air to one end while exhausting gases from the other end.
5. Reversing apparatus for a gas fired regenerative furnace, comprising a gas control device for each gas regenerator, in combination with a reversible blowing device

associated with each gas control devices and operable selectively to supply air to the furnace, or to exhaust products of combustion leaving the furnace by way of the gas regenerator of its associated gas controlled devices.

6. Reversing apparatus for a gas fired regenerative furnace, comprising a gas control device and a blowing device associated with each set of gas and air regenerator passages, each blowing device being operable to supply air to the furnace independently of the gas supplied by its associated gas control device.

7. Reversing apparatus for a gas fired regenerative furnace, comprising a gas control device and a blowing device associated with each set of gas and air regenerator passages, each blowing device being operable to exhaust products of combustion leaving said furnace by way of its associated air regenerator passage and by way of its associated gas control device.

8. Reversing mechanism for a regenerative furnace, comprising blowing devices associated, respectively, with regenerator passages at opposite ends of said furnace, and means for independently reversing each blowing device and for independently controlling the volume of gaseous flow produced thereby.

Dated this 10th day of April, 1922.
GEORGE H. ISLEY.
